UNITED STATES PATENT OFFICE.

ALBERT J. D. OHM, OF OAK PARK, ILLINOIS, ASSIGNOR TO R. WILLIAMSON & COMPANY, OF CHICAGO, ILLINOIS, A CORPORATION OF ILLINOIS.

DESIGN FOR A LIGHTING FIXTURE.

Application filed April 18, 1929. Serial No. 30,875. Term of patent 7 years.

To all whom it may concern:

Be it known that I, ALBERT J. D. OHM, a citizen of the United States, residing at Oak Park, in the county of Cook and State of Illinois, have invented a new, original, and ornamental Design for Lighting Fixtures, of which the following is a specification, reference being had to the accompanying drawing, forming a part thereof, in which—

Fig. 1 is a side elevation of the lighting fixture with a shade shown in broken lines to indicate its position on the fixture.

Fig. 2 is a front elevation of the fixture with the shade also indicated in broken lines; and

Fig. 3 is a top plan view of the fixture also showing the shade in broken lines.

I claim:

The ornamental design for a lighting fixture, as shown.

ALBERT J. D. OHM.
